UNITED STATES PATENT OFFICE.

FRANKLIN L. LANE, OF BELOIT, WISCONSIN, ASSIGNOR TO P. B. YATES MACHINE COMPANY, OF BELOIT, WISCONSIN, A CORPORATION OF WISCONSIN.

ADJUSTMENT FOR WOODWORKING MACHINES.

Application filed September 18, 1920. Serial No. 411,252.

To all whom it may concern:

Be it known that I, FRANKLIN L. LANE, a citizen of the United States, residing at Beloit, Wisconsin, have invented certain new and useful Improvements in Adjustments for Woodworking Machines, of which the following is a specification.

This invention relates to wood working machinery, and especially to wood planing or matching machines into which boards are automatically fed in constant succession.

The invention consists in an improved automatic sizer that is to say, in the mechanism whereby the distance between the cutter heads is adjusted to fit the width or thickness of the boards being feed thereto.

Heretofore two levers have been provided at the operator's station at the rear end of the feeding table, one for adjusting the position of the live corrugated feed roll as the horizontal dimension of the stock on the feed table changes, and another for correspondingly adjusting the position of the side cutter head. The present improvement provides for the accomplishment of both these adjustments by a single lever, whereby greater accuracy and simplicity of operation are attained. It also provides for means for locking the cutter head (and consequently the feed roll also) in any of several adjusted positions corresponding to standard widths of lumber, and for means for making fine adjustments of the roll and cutter head from time to time, as the cutters wear or in setting up the machine.

In the accompanying drawings I have shown only so much of the planing or matching machine and of the automatic feed table as is necessary to illustrate my invention and its application to said machine and table.

Figure 1 is a side elevation of the rear end of the feed table and front end of the planing or matching machine.

Figure 2 is a plan view of the same.

Figure 3 is an end view looking towards the left in Figures 1 and 2 at a point just to the rear of the screw feed roll.

Figure 4 is a cross-section on line 4—4 of Figure 2, and

Figure 5 is a cross-section on line 5—5 of Figure 2.

In these views, 1 represents the planing or matching machine frame, 2 the frame of the feed table and 3 the bed connecting the same. 4 and 5 represent cutter heads of

the planing or matching machine and 6 and 7 the vertical feed rolls of the feed table, roll 6 being corrugated and positively driven, as usual. 8 represents the last of a series of screw rolls of the feed table, which feed the stock forwardly against the inclined end guide 9, and laterally against the side guide 10. The cutter head 4 and the feed roll 6 are laterally adjustable, as usual, to accommodate stock of different horizontal dimensions, but, instead of being separately and independently adjusted, as has heretofore been customary, they are, by the mechanism of the present invention, simultaneously adjusted by the manipulation of a single lever.

This lever, shown at 11, is provided with the usual spring latch 12 and ratchet segment 13, adjustably mounted on standard 35, as shown in Figure 3, and is keyed to the shaft 14 extending rearwardly along the side of the machine. An arm 15, also fast on said shaft 14, is connected by a link 16 with a bracket 17 slidable on a guide rod 18 and connected to the cross-head 19 by a screw rod 20. Cross-head 19 is slidable on the guide rods 21 and 22 (see Figure 3), and carries the corrugated feed roll 6. The purpose of the screw rod 20 is to enable fine adjustments of the roll 6 to be made. Rod 20 is provided with a handle 24 by which it is rotated for the fine adjustments. 23 represents a belt shifter or other control lever.

At its rear end the shaft 14 is journaled in a standard 25 and has keyed to it a forked arm 26, connected by a pair of links 27 with a collar 28 fast on a sleeve 29, slidable in an opening in the frame 1 and having ratchet teeth 30 cut in its lower side. Through the sleeve 29 passes a rod 31, rotatable in said sleeve but prevented from sliding therein by a collar 32 and nuts 33, and threaded at both ends, on its outer end for the reception of said nuts and on its inner end to engage a threaded opening in the side head 4; as will be obvious, the screw rod 31 is for the purpose of making the fine adjustments of the cutter head.

The teeth 30 are spaced apart to correspond to standard dimensions of stock and are engaged by a pawl 34, pivoted on the frame and connected by a link 36 to an arm 37, fast on a shaft 38, journaled in the standards 25 and 35 and having a pedal 39 se-

cured to it in the vicinity of the hand lever 11.

An adjustment of the cutter head 5 is provided for, as shown in Figure 5, by means of the screw rod 45, threaded into said head, passing loosely through the head 4 and journaled in the frame 1.

The end guide 9 is of triangular shape, as shown in Figure 2 and is pivoted at 40 to the bracket 19, carrying the feed roll 6. The guide is provided with a slot 41 in which engages a roller on a pin 42, adjustably mounted on the frame. It will be evident that when lever 11 is actuated to move 15 roller 6 towards or away from roll 7, guide 9 will be moved with it and that the angle of the stock face of said guide becomes steeper as the distance between said rolls increases. At the same time as the roll 6 20 and guide 9 are adjusted, the cutter head 4 is adjusted, the pawl 34 being first disengaged by the pedal 9 and connections. Both cutter head and feed roll and guide are locked in adjusted position by said pawl, 25 and the spacing of the ratchet teeth 30 enables the operator to make his adjustments correspond with standard widths of the stock.

The cutter heads and rolls being set for 30 a given width of stock, when the incoming stock changes in width, say from seven and a half inches to nine and a half inches, the operator steps on the pedal to unlatch the pawl, starts to pull on the lever 11, releases 35 the pedal and pulls lever 11 further until the pawl engages the next tooth 30. The sleeve 29 is interchangeable to suit various sizes of stock being fed. The usual top rolls and other feed rolls on the bed 3, between the feed rolls 6 and 7 and the cutter heads 4 and 5, are not shown in the drawing. 43 in Figure 4 represents a cylindrical guide for the cutter heads and 44 in Figures 1 and 4 a guideway for the lower 40 parts of said heads.

I claim:

1. The combination with a cutter head of a wood working machine and a vertical feed roll of the feed table, of positive means 50 to adjust said head and roll laterally together through equal distances across the work-supporting surface presented by the machine and table, whereby the roll may be moved into lateral engagement with successively entering boards of various sizes and the head will, as a consequence, be set properly to cut each board.

2. The combination with a cutter head of a wood working machine and a vertical feed roll of the feed table, of means to adjust said head and roll laterally across the work-supporting surface presented by the machine and table, including a single operating lever, whereby upon movement of the lever the roll may be moved into lateral

engagement with successively entering boards of various sizes and the head will, as a consequence, be set properly to cut each board.

3. The combination with a planing or matching machine and an automatic feed table therefor, of means for adjusting a cutter head of the machine and a feed roll of the table laterally across the work-supporting surface presented by the machine and table, comprising a shaft connected to both said head and said roll, and a hand lever on said shaft adjacent said roll, whereby upon movement of the lever the roll may be moved into lateral engagement with successively entering boards of various sizes and the head will, as a consequence, be set properly to cut each board. 75 80

4. In a wood working machine, the combination with a cutter head and a feed roll, of a shaft extending along the side of the machine, lever and link connections between said shaft and said head and between said shaft and said roll, a single operating lever on said shaft, and means to lock said shaft in adjusted position. 85 90

5. In a wood working machine, the combination with a cutter head, a feed roll and an end guide, of a slidable member adjustably connected to said head and a slidable member adjustably connected to said roll and guide, and a common actuating means for sliding said members transversely of the machine. 95

6. In a wood working machine, the combination of a cutter head, a feed roll, slidable members carrying said head and roll respectively, a common actuating means for said members, and a readily operable clutch device to lock the said actuating means in adjusted position, whereby the head and roll may be instantaneously set and locked in a new position for each board of different standard size as it enters the machine. 100 105

7. In a wood working machine, the combination with an adjustable cutter head and an adjustable feed roll, and a positive connection between the same, means to actuate said connection to adjust said head and roll together, a readily operable clutch device to lock them in adjusted position, and means to unlock them located adjacent to said actuating means, whereby the head and roll may be instantaneously set and locked in a new position for each board of different standard size as it enters the machine. 110 115 120

8. In a wood working machine, the combination with a cutter head slidable transversely of the machine, a feed roll and end guide for the stock likewise slidable transversely of the machine, a longitudinal oscillatable shaft, levers on said shaft connected to said head and roll respectively, a hand lever to turn said shaft located adjacent said roll and guide, a pawl to lock said slidable 125 130

- cutter head in adjusted position, a shaft connected to actuate said pawl, and a treadle on said last mentioned shaft located adjacent to said hand lever.
9. In a wood work machine, the combination of a transversely slidable cross-head at the front end of the feed table, a corrugated feed roll carried thereby and an inclined end guide pivoted thereto, a fixed pin 40
10 gaging a slot in said guide, whereby the angle of said guide varies, as said cross-head is moved, an arm slidable parallel to said cross-head, a screw rod connecting said arm and cross-head, and a hand lever to slide said 45
15 arm.
10. In a wood working machine, the combination of a transversely slidable cutter head, a sleeve adjustably connected to said cutter head for transmitting movement thereto and provided with ratchet teeth, means to slide said sleeve, a pawl pivoted to engage said teeth, and a treadle to disengage 50
20 said pawl.
11. In a wood working machine, the combination of a transversely slidable cutter head, a hollow sleeve having ratchet teeth, a rod journaled against longitudinal movement in said sleeve and threaded into said cutter head, links pivoted to said rod, a lever 55
25 pivoted to said links, a shaft on which said lever is mounted, a transversely slidable feed roll connected to said shaft, a hand lever for actuating said shaft located in the vicinity of said feed roll, a pawl engaging said teeth
30
35 means located in the vicinity of said hand lever for disengaging said pawl, and means for adjusting said feed roll relative to said shaft.
12. In a wood working machine, the combination with the adjustable cutter heads 40 and feed roll, of a slidable member to which one of said cutter heads is adjustably connected, a lever connected to said slidable member, a shaft on which said lever is mounted, a slidable member to which said roll is connected, a slidable arm having an adjustable connection with said member, a lever on said shaft connected to said arm, a hand lever for actuating said shaft located opposite said feed roll, a pawl for locking 50
45 one of said sliding members in adjusted position, and a treadle located in the vicinity of said hand lever and connected to said pawl to disengage the same when said cutter head and roll are to be adjusted. 55
13. A wood working machine comprising a table or bed, means thereon for guiding one side of a piece of work travelling on said bed, a cutter and a feed roll in advance thereof, both projecting above said bed with their axes transverse to the work receiving surface thereof; the said bed and guiding means extending in advance of said feed roll sufficiently to support the work in contact with the guiding means in position to be engaged by the feed roll and forced thereby against and along the guiding means, and means for simultaneously and equally transversely moving said cutter and feed roll toward said 60
65 guiding means. 70
- In testimony whereof I have hereunto subscribed my name in the presence of two subscribing witnesses.
